UNITED STATES PATENT OFFICE.

JOSEPH E. MYERS, OF TACOMA, WASHINGTON.

BLADE HOLDER.

Application filed August 6, 1921. Serial No. 490,207.

To all whom it may concern:

Be it known that I, JOSEPH E. MYERS, a citizen of the United States of America, and a resident of Tacoma, county of Pierce, and a resident of Washington, have invented certain new and useful Improvements in Blade Holders, of which the following is a specification.

My invention relates to a device for holding a removable blade, and has for its object improvements in such devices.

In the accompanying drawings

Fig. 1 is a perspective view;

Fig. 2 is a side elevation with the blade shown in section; and

Fig. 3 is an enlarged sectional elevation of the blade and part of the holder for the purpose of more clearly showing the construction.

The blade B is a discarded safety razor blade which it is intended to utilize for cutting or scraping purposes. The holder for the blade is composed of thin sheet metal bent back upon itself so as to form a pocket P within which one edge of the blade rests. The width of the holder is preferably the same, or nearly the same, as the length of the blade to be held.

On one side of the pocket P the metal is bent back again upon itself and extends downward to form a handle or a projection K which is inserted into a wooden handle W.

On the other side of the pocket, there is a central upwardly projecting tongue T which is arranged to extend through the central opening in the blade B, as clearly shown in Fig. 3.

The metal of which the holder is made is somewhat resilient, and the spring in the tongue T acts to hold the blade in place in the holder. When the blade is used for cutting or scraping, the pressure on the cutting edge tends to force the blade and holder toward each other. But by pulling the blade upward and the holder downward, the spring of the tongue T yields and the parts may be separated by a moderate force. When the parts are separated, they may be assembled by moving them toward each other along paths which are the reverse of those through which they travel when being separated.

What I claim is:

A blade holder consisting of resilient sheet metal bent back twice upon itself so as to form a double fold, one of said folds being in the form of a pocket to receive a blade, said holder having a part projecting in one direction from said folds to form a handle and another part projecting in the opposite direction from said folds and serving to hold a blade in said pocket.

JOSEPH E. MYERS.
